Atty.

UNITED STATES PATENT OFFICE.

WALTER BROWN, OF WEBSTER GROVES, MISSOURI, ASSIGNOR OF ONE-HALF TO
ARTHUR B. BIRGE, OF ST. LOUIS, MISSOURI.

STAY-BOLT-CUTTER CLAMP.

1,122,364.

Specification of Letters Patent. Patented Dec. 29, 1914.

Application filed January 9, 1914. Serial No. 811,200.

To all whom it may concern:

Be it known that I, WALTER BROWN, a citizen of the United States, residing at Webster Groves, Missouri, have invented a 5 certain new and useful Improvement in Stay-Bolt-Cutter Clamps, of which the following is a full, clear, and exact description, such as will enable others skilled in the art to which it appertains to make and use the 10 same, reference being had to the accompanying drawings, forming part of this specification, in which—

Figure 1 is a longitudinal section illustrating my improved clamp in position on a 15 stay bolt cutter. Fig. 2 is a front view of my improved clamp in position. Fig. 3 is a section on line 3—3 of Fig. 2. Fig. 4 is a bottom view of Fig. 2.

My invention relates to metal working 20 tools and specifically to a device adapted to hold the tool and work in proper relationship.

Specifically my invention relates to a 25 form of clamp adapted for use on a stay bolt cutter of the form claimed in my co-pending application No. 744,966, or similar tool, the purpose being to hold the stay bolt against rotation, or longitudinal displacement relative to the cutter.

30 The principal object of my invention is to provide a clamp of the sort described which is economical to manufacture and which is simple and easy to operate, strong and positive in its action and not liable to get out 35 of order.

Other objects of my invention will be hereinafter pointed out or will be obvious upon an understanding of the device and its operation.

40 As illustrated in the accompanying drawings, 1 represents the barrel of a stay bolt cutter or similar tool in which are carried the cutters 2 which are suitably actuated by power driven mechanism, and in which barrel 45 is an axially disposed work receiving portion 3. It is obvious that these cutters may be for the purpose of severing the stay bolt 4 of a boiler, or for shaping or otherwise working upon other bar like or

50 tubular pieces. It is obvious that rotation of the cutters 2 has the tendency to rotate the stay bolt also, or if the stay bolt were held against rotation, the tendency would be to longitudinally displace the tool upon the 55 stay bolt. As a means of preventing such

action, and of positively securing the work and tool in the proper relationship, I provide a clamping device which comprises a tripod or frame member 5 which is secured to the barrel 1 in any proper fashion so 60 as to rotate thereon. As shown, the connection consists of a clamping ring 6 secured to the barrel and carrying the stationary bearing ring 7, which forms a rearward abutment for the frame member, and one 65 or more securing rings 8 which are threaded or clamped upon the barrel 1 and form forward abutments for the frame member. The frame member is provided with a rearwardly extending skirt portion 9 which 70 covers and protects the bearing and rear abutment, and an annular depending portion 10 which travels intermediate the rear and forward abutment members. The annular depending portion 10 carries a movable bearing ring 11, which, with the stationary bearing ring 7, form runways for the ball bearings 12. The frame member has forwardly projecting leg portions 14, 75 preferably three in number, the forward 80 extremities of which are grooved to provide the proper guideways for the clamping plate 15. The guideways are formed so as to prevent longitudinal displacement of the clamping plate 15 relative to the 85 frame member 5, but so as to permit a limited sliding movement which is in a vertical direction when the device is in a position as illustrated in Figs. 1 and 2. The clamping plate 15 has a mounting 16 90 for clamping screw 17, and an expansion spring 18 is interposed between the mounting 16 and one leg 14 of the frame member. The tendency of the spring 18 is to press the clamping plate 15 in an upward 95 direction as illustrated, or more specifically in a direction transverse of the longitudinal axis of the work receiving portion 3 of the tool.

The clamping plate 15 is provided with 100 an aperture 19 which lies in front of the work receiving portion 3 when the clamping plate 15 is sufficiently depressed against the influence of spring 18. The tendency of spring 18, however, is to displace clamping plate 15, as above described, so as to throw the aperture 19 out of alignment with the work receiving portion 3. Aperture 19 may be of any proper contour to accommodate 105 the piece upon which the tool is intended 110

to work. The form herein illustrated is designed for use on a stay bolt cutter and consequently is provided with an irregular shaped aperture of size and form such as 5 to insure its making contact with a stay bolt inserted through the aperture and into the work receiving portion 3. The clamping plate at the edge of the aperture 19 is cut with a series of serrations 20 which operate after the fashion of an alligator or pipe wrench to bite into the piece being worked upon, and prevent its rotating.

The operation of the device is as follows: The stay bolt or other piece to be worked 15 on is inserted through the aperture 19 and into the work receiving portion 3. When the cutters 2 are thrown into engagement with the work it brings the work into alignment on the longitudinal axis of the tool, 20 thereby drawing down the clamping plate against the influence of spring 18. Spring 18 being thus under tension, it holds the serrations 20 in firm engagement with the work, thereby holding the work against rotation with the tool or longitudinal movement. The frame and sliding plate may be held against rotation by any convenient means such as by the engagement of the projecting portion of clamping screw 17 with 25 a stationary object.

I am aware that the device herein illustrated is capable of various modifications and changes in detail, and for that reason, I do not intend that the language of the 35 claims be limited to the specific form disclosed.

I claim:

1. In a rotary tool, the combination of 40 cutters, means for moving the cutters into engagement with work presented to the action of the tool, a clamping device adapted to engage work presented to the action of the cutters, said clamping device and said cutters having relative rotary movement, 45 the construction and arrangement of parts being such that the engagement of the cutters with the work forces the work into engagement with the clamping member, whereby the work is held against movement 50 relative to the clamping member.

2. In a tool of the class described, rotary 55 cutters mounted to engage work presented to the action of the tool, a clamping member adapted to engage work presented to the action of the tool, said clamping member being provided with means whereby it may be held against rotation with the cutters, the cutters operating to force the work into engagement with the clamping member, the clamping member being provided with means whereby it retains the work against movement relative thereto.

3. In combination with a rotary tool, a 60 frame member supported thereon and arranged to permit rotation of said tool inde-

pendently thereof, and a spring operated clamping device supported by said frame member and adapted to engage work presented to the action of said tool to hold the same against rotation with said tool. 70

4. In combination with a tool having a rotating cutter, a clamping device supported on said tool and provided with spring pressed means for engaging an article presented to the action of said tool to retain 75 said article against movement with said cutter.

5. In combination with a tool having an axial work receiving portion and a cutter 80 revoluble about the same, a clamping member supported on said tool so as to permit rotation of said cutter independently thereof, said clamping member including means for holding an article placed in said work receiving portion against movement with 85 said cutter, the cutter operating to force the work into engagement with the clamping member.

6. In a tool having cutters revoluble about a work axis, a clamping member supported 90 on the tool and provided with means adapted to engage work disposed in the work axis of the tool to hold the same against rotation with the tool, the cutters being operable to move work into operative engagement 95 with said clamping member.

7. In combination with a tool having rotary cutters adapted to operate upon an article disposed in the work axis of the tool, a work retaining device mounted on the tool 100 so as to permit rotary movement of the cutters independently thereof, said work retaining device including a member movable transversely of the work axis of the tool 105 under spring pressure, which member is provided with means for engaging material presented to the action of the cutters.

8. In combination, a rotary tool having cutters operating about a work axis, a frame 110 rotatably mounted on said tool, a sliding plate supported on said frame, said sliding plate being provided with work engaging means, and yielding pressure means for holding said sliding plate in operative position to hold the work against movement 115 relative thereto.

9. In combination, a rotary tool having an axial work receiving portion and cutters operating about said work receiving portion, a frame mounted on said tool and movable 120 relatively independently of said cutters, a retaining member supported on said frame and movable across the work axis of the tool, said retaining member having a work receiving aperture adapted to be alined on the work axis of the tool, and yielding pressure means coöperating with said retaining member adapted to displace the apertured portion thereof from the work axis of the tool, said retaining member being provided 125 130

with means for engaging an article placed in said aperture.

10. In combination with a tool having rotating cutting members, a clamping member mounted on said tool and having a work engaging portion positioned in front of said cutting members, said clamping member being spring-pressed to hold the work against movement relative thereto.
11. In a rotary tool, the combination of a cutter and a clamping device, mounted for relative rotary movement, said clamping device having a work engaging portion adapted to engage work presented to the action of the tool, and means for moving said cutter to render said clamping device effective to engage and retain work presented to the action of the cutters.
12. The combination of a tool, and a

clamping device mounted for relative rotary movement, said tool including means for forcing the clamping device into operative position through the medium of work presented to the action of the tool.

13. In a device of the class described, a clamping device adapted to engage work to hold it against movement relative thereto, and a rotary cutter adapted to operate upon the work and hold the same in engagement with the clamping device.

In testimony whereof I hereunto affix my signature in the presence of two witnesses, this 6th day of January, 1914.

WALTER BROWN.
